CARBON DIOXIDE REFRIGERATING UNIT

Charles A. Clarke, New York, N. Y., assignor of
one-half to Norman Paul, Brooklyn, N. Y.

Application March 24, 1937, Serial No. 132,716

8 Claims. (Cl. 62—91.5)

My invention relates to a refrigerating cooling unit and refers more particularly to a refrigerating unit that uses carbon dioxide as a cooling agent.

5 One object of my invention is to provide a cooling unit that can be placed in a conventional refrigerator and maintain the desired temperature by the use of carbon dioxide ice.

Another object of my invention is to provide a 10 refrigerator cooling unit that cools the refrigerator by means of carbon dioxide ice and freezes a multiple of ice cubes and/or ice cream or the like.

A further object of my invention is to provide 15 a refrigerator cooling unit that automatically maintains a desired temperature so constructed that the whole device is but the assembly of a group of inexpensive elements or parts, that puts it within the reach of all.

20 One feature of my invention is to provide a refrigerator unit wherein carbon dioxide ice is enclosed in a perforated insulated covering and held or supported centrally within an inner container with a multiple of perforations therein, 25 which container is enclosed by another third container that also encloses a fourth container made integral with the inner container, the inner container provided with a detachable door and the fourth container provided with means 30 slidably holding one or more ice cube trays, the third container having an outlet provided with an adjustable temperature controlling device.

Another feature of my invention is to provide 35 a refrigerating unit adapted to hold carbon dioxide ice in such a manner that the sublimated carbon dioxide gas is circulated around the carbon dioxide ice in three separate independent circulations superimposed upon and arranged around each other.

40 Another valuable feature of my invention is to provide a refrigerating unit with three separate gas circulations and a multiple of fins arranged around the outside of the unit.

45 A further valuable feature of my invention is to provide a refrigerator unit with three superimposed gas circulations, the first circulating around carbon dioxide ice arranged within an enclosure that is not gas tight, the second circulation being around the first enclosure that is arranged within a container provided with a 50 detachable door and perforations communicating with a third circulation within a finned container arranged around the second and also around an 55 enclosure adapted to slidably hold one or more

ice cube trays therein, the finned container provided with a temperature controlled outlet.

I attain these objects preferably by the means illustrated in the accompanying drawings where- 5 similar numerals refer to like parts throughout the several views, in which:

Figure 1 is a partial longitudinal section of the device.

Figure 2 is a front view with the door removed.

Figure 3 is a diagrammatic view of the circula- 10 tion.

Figure 4 is an isometric view of the support for the carbon dioxide ice.

The device consists of a front frame 1, with 15 openings 2 and 3, for the ice cube drawers 4 and 5, and an opening 6, with four pair of ears 7, 8, 9 and 10, carrying the eyebolts 11, 12, 13 and 14, that are provided with locking nuts 15, 16, 17 and 18, which eyebolts are pivoted in the ears by the pivots 19, 20, 21 and 22, and are 20 used to removably hold the door 23, that is provided with four projecting slotted ears, slidably engageable with said eyebolts, two of which are shown in Figure 1 by 24 and 25 and this door 23, is detachably held by these eyebolts in gas seal to the carbon dioxide ice chamber 32, by the 25 washer 26.

This front frame 1, is provided with a boss 27, 30 for holding a safety device 28, communicating with the inside of the carbon dioxide ice container 32, said safety device having a body 29, that is screwed to the boss 21, and this body carries a screw cap 30, for holding an explosion disc 31, made of any suitable material and of any suitable thickness, so that when the pressure exceeds that to which the disc 31 will hold, the disc will break and release the pressure within the chamber 32, which pressure might occur but is not likely to, thus preventing an explosion.

35 There is another boss 33, arranged upon this frame 1, for holding an adjustable gas release or temperature control 34, that is comprised of a body 35, communicating with the space 36, by the opening 37, shown in Figure 1.

This gas release or temperature control 34, 45 is provided with a tapered cock 38, with a split extension 39, to which is fixed one end of a bimetal helix 40, of suitable construction and proportion the other end 41, connected to a gear 42, that is adapted to position the bimetal helix 40, by means of the pinion 43, and handle 44, so that when the temperature of the refrigerator reaches the desired point, the bimetal helix will move and open the valve 38, thus releasing the gas pressure.

The back piece 45, holds, together with the front piece 1, a rectangular tube 46, provided with a multiple of holes 47 to 52 inclusive, that communicated with the gas space 36.

5 Directly below this rectangular box or tube 46, is a space 53 enclosed in gas seal by the wall 54, clearly shown in Figure 3, within which space 53, are slidably arranged the ice cube drawers 4 and 5.

10 Outside of this space 36, is an enclosure 55, that carries all around the enclosure the cooling fins 56 to 69 inclusive.

The carbon dioxide ice 70, shown in Figures 2 and 3, is enclosed in an insulated cover 71, that 15 is not gas tight, and this carbon dioxide ice together with the insulated cover 71, is supported in the chamber 32, by the support 72, shown in Figure 4, which support is provided with a multiple of legs four of which are shown in Figure 4, by the 20 numerals 73 to 76 inclusive and to this support is fixed an insulated piece 77, by the rivets 78 to 81 inclusive, so that when the carbon dioxide ice with its insulated enclosure 71, is supported by the support 72, the gas sublimated from the 25 carbon dioxide ice 70, will circulate around the ice within the enclosure 71 and outside the closure within the box 32, through a multiple of holes 82, 83 and 84, shown in Figure 2, in the direction of the arrows shown in Figures 2 30 and 3, or through the openings that may be in a covering that is not gas tight, such as paper or the like.

The gas, after circulating as aforesaid, passes through the openings 47 to 52 inclusive, in box 35 46, into and around the space 36, and around the space 53, adjacent to the space 32, finally passing through the temperature control valve 34.

It is obvious that the space 53, will be cooled twofold, first, by convection from the bottom wall 40 of the box 46, of the chamber 32, and secondly, from the cool gas that passes around the chamber in the space 36, by convection through the wall 54, and that the refrigerator will be cooled by the cooling of the fins 56 to 69 inclusive and 45 the ends 1 and 45 of the device and that the control of the temperature of the refrigerator by the fins and the device body, will be controlled by controlling the sublimation of the carbon dioxide ice by the opening and closing of the 50 control valve 34.

It is further obvious that with the front 1, back 45, cover 23, control unit 34, safety device 28 made of die castings, the box or chamber 46, enclosures 54 and 55, can be cheaply and easily 55 attached together in gas seal with the front 1 and back 45, and that the fins 56 to 69 inclusive cheaply stamped out and attached in close contact with the enclosure 55 and that the support 72, and the ice cube drawers 4 and 5, can be 60 cheaply stamped out of aluminum or the like, so that the whole device can be made inexpensive and sold within the means of all.

Furthermore this device can be placed in any conventional refrigerator or place, supply ice 65 cubes or supply ice cubes and ice cream, etc. simultaneously, while at the same time will cool the ice box, with the use of no machinery or have any moving parts to wear out, no water to mop up or drain away and it can be operated for a few cents 70 a day, only requiring to be serviced once a week.

Having thus illustrated and described the preferred embodiment of my invention, I do not wish to limit myself to the exact construction or arrangements of parts shown, as it is evident 75 that modifications may be made therein without

departing from the spirit of the invention or scope of the claims.

I claim:—

1. The combination in a refrigerating unit of a carbon dioxide ice chamber, a detachable cover therefor, an ice tray chamber thereunder, means in said ice tray chamber slidably holding an ice tray, an ice tray, a ribbed casing adapted to utilize the refrigerating effect of gases from said ice chamber, said casing spaced from said chamber and partially enclosing the said chambers providing a space therearound, an inlet from the carbon dioxide ice chamber to said space, and an outlet from said space to the atmosphere. 10

2. The combination in a refrigerating unit of a carbon dioxide ice chamber, a detachable cover thereupon, a sealing gasket for the said cover, detachable clamping means for said cover, an ice tray thereunder, means in said ice tray chamber slidably holding an ice tray, a casing with a plurality of ribs thereupon adapted to rapidly utilize the refrigerating effect of gas from said ice, said casings spaced from said chambers and partially enclosing the said chambers providing a space therearound, a plurality of inlets from the carbon dioxide ice chamber to said space, and an outlet from said space to the atmosphere remote to said inlet. 15

3. The combination in a refrigerating unit of a carbon dioxide ice chamber, a detachable cover thereupon, a sealing gasket therefor, detachable clamping means for said cover, an ice tray chamber thereunder, means in said ice tray chamber slidably holding a plurality of ice trays, a casing spaced from said chambers partially enclosing the said chambers providing a space therearound, a plurality of fins integral with said casing, adapted to rapidly utilize the refrigerating effect of the gas from the said ice chamber, an inlet from the carbon dioxide chamber to the said space and an outlet from said space to the atmosphere remote to said inlet. 30

4. The combination in a refrigerating unit of a carbon dioxide ice chamber, a detachable cover thereupon, a sealing gasket for the said cover, detachable clamping means for the said cover, an ice tray chamber thereunder, means in said ice tray chamber slidably holding a plurality of ice trays, a plurality of ice trays, a casing spaced from said chambers partially enclosing said chambers providing a space therearound, a plurality of fins arranged upon said casing adapted to rapidly utilize the refrigerating effect of the gas sublimated in the said ice chamber, an inlet from the carbon dioxide ice chamber to said space, and an adjustable outlet from said space to the atmosphere. 40

5. The combination in a refrigerating unit of a carbon dioxide ice chamber, a detachable cover thereupon, a sealing gasket for the said cover, detachable clamping means for the said cover, an ice tray chamber thereunder, said ice chamber and ice tray chamber integral with each other, means in said ice tray chamber holding a plurality of ice trays, a plurality of ice trays, a casing spaced from said chambers partially enclosing said chambers providing a space therearound, a plurality of fins arranged upon said casing, adapted to utilize the refrigerating effect of gas sublimated in said ice chamber, an inlet from the carbon dioxide ice chamber to the said space and a temperature controlled outlet from said space to the atmosphere. 60

6. The combination in a refrigerating unit of a carbon dioxide ice chamber, an insulated enclo- 70

sure with perforations therein holding carbon dioxide ice, means supporting said insulated enclosure and ice, a detachable cover thereupon, a sealing gasket for said cover, detachable clamping means for said cover, an ice tray chamber thereunder, said ice chamber and ice tray chamber integral with each other, means in said ice tray chamber holding an ice tray, a casing provided with a multiple of outwardly projecting fins 5 and spaced from said chambers, partially enclosing same providing a space therearound, and inlets from the carbon dioxide ice chamber to said space, and an adjustable temperature controlled valve attached to said outlet remote from 10 said inlets.

7. The combination in a refrigerating unit of a carbon dioxide ice chamber, a safety pressure gas releasing outlet means in said chamber, a perforated insulated enclosure holding carbon dioxide ice, insulating means supporting said enclosure and ice in spaced relation to said chamber, a detachable cover on said chamber, a gasket 15

and clamping means for the cover, an ice tray chamber integral thereunder, a plurality of ice trays, a ribbed casing around said chambers arranged to provide a space therearound, said ribs adapted to utilize the refrigerating effect of the gas sublimated from said ice, and inlets from said chamber to said space and an outlet to said space remote to said inlet connected to a temperature control valve. 5

8. The method of refrigerating using carbon dioxide ice which comprises placing the ice in a perforated insulated container in spaced relation to another container, causing gas sublimated from said ice to pass slowly from said perforated container into and around said second container, causing said gas to pass around an enclosing space partially surrounding the said second mentioned container, and causing said gas to pass through a temperature controlling device, said circulation being caused by natural convection. 10 15 20
